DESIGN FOR A SMOKER STAND

Maurice E. Olin, Vancouver, Wash.

Application June 13, 1945, Serial No. 120,053

Term of patent 14 years

(Cl. D85—2)

To all whom it may concern:

Be it known that I, Maurice E. Olin, a citizen of the United States, residing at Vancouver, in the county of Clark and State of Washington, have invented a new, original, and ornamental Design for a Smoker Stand, of which the following is a specification, reference being had to the accompanying drawing, forming part thereof.

I claim:

The ornamental design for a smoker stand, as shown.

MAURICE E. OLIN.
